[57] CLAIM

The ornamental design for a container neck, as shown and described.

DESCRIPTION

FIG. 1 is a perspective view of the container neck showing the new design.

FIG. 2 is a side view thereof, the opposite side being symmetrical.

FIG. 3 is a top view thereof.

FIG. 4 is a front view thereof, the back view being symmetrical; and,

FIG. 5 is a bottom view thereof.

The broken line showing of a container is for illustrative purposes only and forms no part of the claimed design.
